FIG. 1

FIG. 2

FIG. 3

FIG. 4

FIG. 1 is a top perspective view of our new design for a hollow half-round file.

FIG. 2 is a bottom perspective view thereof;

FIG. 3 is an enlarged end view thereof; and

FIG. 4 is a perspective view of the file projections.

The arced lines on the inner and outer surfaces of the hollow half-round file are understood to be representative of projections extending from the surfaces constituting the characteristic features of the file as best seen in FIG. 3.

We claim:

The ornamental design for a hollow half-round file, substantially as shown and described.
